UNITED STATES PATENT OFFICE.

OLIVER A. MEYERS, OF CLEVELAND, OHIO.

DEVICE FOR INTRODUCING AIR TO THE CARBURETED MIXTURE FOR AN INTERNAL-COMBUSTION ENGINE.

1,200,006.

Specification of Letters Patent.

Patented Oct. 3, 1916.

Application filed December 26, 1913, Serial No. 808,633. Renewed June 24, 1915. Serial No. 36,151.

To all whom it may concern:

Be it known that I, OLIVER A. MEYERS, a citizen of the United States, residing at Cleveland, in the county of Cuyahoga and State of Ohio, have invented a certain new and useful Improvement in Devices for Introducing Air to the Carbureted Mixture for an Internal-Combustion Engine, of which the following is a full, clear, and exact description.

This invention relates to a device for introducing air into the manifold of an internal combustion engine, between the intake valves for the engine and the carburetor.

Generally speaking, the invention comprises the elements and combinations thereof set forth in the accompanying claims.

Reference should be had to the accompanying drawings forming a part of this specification, in which—

Figure 1 shows in elevation the manifold of an engine with the device of my invention mounted thereon, and a heating device by which the air passing through the device of my invention is priorly heated. Fig. 2 is a sectional elevation of the device of my invention. Fig. 3 is a section on the line 3—3 of Fig. 2; and Fig. 4 is a cross section showing a modified form of my device.

For some time it has been generally recognized that it is advantageous to introduce air into the fuel mixture before it passes into the cylinder or cylinders of the engine, and there have heretofore been devices provided for accomplishing this purpose. These devices, however, have been, so far as I am aware, of such a construction as to necessitate the use of valves for the regulation of the quantity of air supply. This has the disadvantage that if perchance the driver of the car neglects to shut off his air valve when the engine is stopped and subsequently endeavors to start the engine with the air valve open, the engine will probably not respond, due to an excess of air in the gas mixture.

My device works entirely automatically, so that no attention need be given to the device, after it is installed.

As illustrative of the manner in which my device is applied, there is shown in Fig. 1 at 1 the manifold of an engine, and secured in this manifold is the device of my invention generally represented at 2. Connected with the device 2 is a flexible hose 3, which may be secured to the device 2 in any desired manner, and for the purpose I use pins such as shown at 4, carried by the hose, which are caused to enter right angle grooves, as at 2^a, in my device, the groove and pin forming a bayonet joint and thereby securely holding the hose 3.

Around the exhaust pipe from the engine, which is represented at 5, I would place a chambered member 6,—this member being split and held together in any suitable manner, as by a bolt such as represented at 7. As will be seen from the drawing, the casing is hollow and is provided with one or more inlet ports by which air may enter into the casing and coming into contact with the exhaust pipe, the air will be heated. This casing is provided with a neck 8 which has formed therein a groove 8^a, the groove co-operating with a pin 9, which is carried by the pipe 3, the two forming a bayonet joint. It will be understood that the description with respect to the groove 8^a and the pin 9 is duplicated upon the opposite side of the pipe.

It will be obvious that as the pistons within the cylinders of the engine are reciprocating and producing a suction, this suction will operate to draw air through the sleeve 6, pipe 3 and to the device of my invention represented at 2.

In Figs. 2 and 3 and 4 is illustrated the particular device for controlling the rate of flow of air which is delivered to the manifold.

The device comprises a two-part casing, represented at 10 and 11,—these being secured together, preferably by a screw thread engagement. The portion 10 of the device is preferably cylindrical in form, and at one end is provided with a hollow exit neck represented at 10^a, the diameter of the inside of the exit neck being less than the internal diameter of the main portion 10, so that a

shelf is formed at the end of the neck 10^a, and this shelf supports a series of layers of foraminous material and fibrous material.

The foraminous material, which I employ, is screen disks of small mesh, and these disks are preferably circular, and of a diameter which is slightly less than the internal diameter of the portion 10. The fibrous material which I employ is preferably cloth and is likewise in the form of disks. In placing this foraminous and fibrous material within the portion 10, I superimpose a number of disks of screen material, as represented at 12. Then I place 15 a layer of fibrous material or cloth, as indicated at 13. Upon this is placed a second layer or pile of screen disks, the same as those described at 12, and so on in succession I use a stack or pile of disks of screen 20 material, which stacks are separated by a layer of fabric. When this material has been placed within the receptacle 10, the portion 11 is screwed in and will hold the screen material and the cloth material in 25 place.

The end of the neck portion 10^a is screw threaded, and is adapted to coöperate with screw threads formed in the wall of an opening into the manifold 1. Below the 30 screw threads the portion 10^a carries a cylindrical drum 14 formed of foraminous or screen material, and extends within the manifold 1. This cylindrical portion 14 serves to cause the added air and the fuel 35 mixture to be thoroughly mixed with each other.

The action of my device seems to be as follows: The suction produced by the engine when running tends to cause a movement 40 of the disks in such a manner as will produce a movement of the disks in accordance with the suction produced by the engine when running. The position of the disks will be changed in accordance with 45 the variation in the suction produced, and this movement of the disks will control the quantity of air passing through the device of this invention. The air apparently 50 passes around the edges of the disks in greater quantities than it does through the body of the disks itself, and the disks move in a manner as to permit increased quantities of air to be supplied to the engine as the suction of the engine increases.

55 I have found that if this device be adjusted so that the engine will run on low speed the higher speeds will be automatically taken care of. That is to say, if the packing of fabric and screen disks is so 60 arranged as to quantity and compression that the engine runs satisfactorily on low speed, it will be unnecessary to further adjust the device for other speeds of the engine.

65 With the device of this invention I have

found that the engine works much more efficiently. That is to say, less gasolene is required to maintain a given speed of the engine, when using this device, than is the case when the same speed of the engine is 70 maintained without using the device of my invention.

It may be found desirable to form grooves such as indicated at 15 in Fig. 4, in the inner wall of the casing 10, to thereby admit 75 a greater amount of air than in the present arrangement. This I consider entirely within the spirit of my invention.

Having thus described my invention, 80 what I claim is:

1. In an auxiliary air admission device 85 for gas engines, comprising a casing having an inlet and an outlet, a plurality of flexible foraminous disks within the casing, the edges of said disks being adjacent the wall 90 of the casing and unsecured whereby the disks may have limited movement within the casing to control the quantity of air passing through the casing, and means for holding said disks within the casing. 95

2. In an auxiliary air admission device 100 for gas engines, the combination with a casing having an inlet and outlet opening, a plurality of compacted flexible disks within said casing, the edges of said disks 95 being adjacent the wall of the casing and unsecured whereby the disks may have a limited movement within the casing to control the passage of air through the casing, and means for holding the disks within the 105 casing.

3. In an auxiliary air admission device 110 for gas engines, the combination with a hollow casing having an inlet and outlet 105 opening, a body of foraminous flexible material within said casing, said material being unsecured at the portion adjacent the casing whereby the body of material may have a limited movement within the casing, thereby to control the passage of air 110 through the casing, and means for holding the porous material within the casing.

4. An auxiliary air admission device 115 for gas engines, comprising a casing having an inlet and outlet opening, a plurality of 115 stacks of foraminous flexible material interspersed with layers of fibrous material within said casing, the edges of the foraminous and fibrous material being adjacent the wall 120 of the casing and unsecured whereby the material may have a limited movement within the casing to control the passage of air through the casing, and means for holding said material within the casing. 125

5. The combination with a manifold of 125 an internal combustion engine, of a casing carried by said manifold, said casing having an inlet and outlet opening, means for delivering air to the inlet opening of said casing, a body of foraminous compactible 130

1,200,000

8

material within said casing, said material being unsecured at the portion adjacent the wall of the casing whereby the body of material may have a limited movement 5 within the casing to control the passage of air through the casing, and means for holding the foraminous material within the casing.

In testimony whereof, I hereunto affix my signature in the presence of two witnesses.

OLIVER A. MEYERS.
